The ornamental design for a dual port antenna assembly, as shown and described.

DESCRIPTION

FIG. 1 is a top perspective view of a dual port antenna assembly, showing our new design;

FIG. 2 is a top view thereof;

FIG. 3 is a front view thereof;

FIG. 4 is a side view thereof;

FIG. 5 is a bottom view thereof;

FIG. 6 is a top perspective view of one of the dual port antenna of FIG. 1;

FIG. 7 is a front perspective view of the dual port antenna of FIG. 6;

FIG. 8 is another top perspective view of the dual port antenna of FIG. 6;

FIG. 9 is another front perspective view of the dual port antenna of FIG. 6;

FIG. 10 is a top rear perspective view of the dual port antenna of FIG. 6;

FIG. 11 is a rear perspective view of the dual port antenna of FIG. 6;

FIG. 12 is a rear view of the dual port antenna of FIG. 6;
FIG. 13 is a front view of the dual port antenna of FIG. 6;
FIG. 14 is a right side view of the dual port antenna of FIG. 6;

(Continued)

FIG. 15 is a left side view of the dual port antenna of FIG. 6; and,

FIG. 16 is a top view of the dual port antenna of FIG. 6. Each of the dual port antennas provided on the top surface of the article are identical in appearance to the dual port antenna depicted in FIGS. 6-16.

The broken lines shown in FIGS. 1-5 depict components of the dual port antenna assembly that form no part of the claimed design and are included for environmental purposes only.
